RADIO RECEIVER

Guy Poisson, Prairie Village, Kans., assignor to
Torotel, Inc., Grandview, Mo.

Filed Jan. 17, 1972, Ser. No. 218,633

Term of patent 14 years

Int. Cl. D14—03

U.S. Cl. D56—4 B

FIG. 1 is a front elevational view of a radio receiver, showing my new design;

FIG. 2 is a top plan view;

FIG. 3 is a bottom plan view;

FIG. 4 is a fragmentary right side elevational view;

FIG. 5 is a fragmentary left side elevational view; and

FIG. 6 is a rear elevational view thereof.

A portion of the antenna in FIGS. 4 and 5 has been broken away and omitted for convenience in illustration.

I claim:

The ornamental design for a radio receiver, as shown and described.
